UNITED STATES PATENT OFFICE

WALTER KLEINOW, OF HENNIGSDORF, GERMANY, ASSIGNOR TO GENERAL ELECTRIC COMPANY, A CORPORATION OF NEW YORK

PULVERIZED COAL FIRING WITH SUBDIVIDED FLAME

Application filed October 22, 1929, Serial No. 401,551, and in Germany November 6, 1928.

The present invention relates to pulverized-coal firing with subdivided flame in which the device for introducing the pulverized coal consists of a nozzle tube or tubes with a multiplicity of adjacent outlets for ejecting into the furnace the mixture of coal dust and air in individual jets. Heretofore it has been the practice to inject the fuel at substantially right angles to the axial direction of the tube or tubes, and to introduce combustion air at substantially right angles to the direction of injection of fuel. If two parallel nozzle tubes are provided at the lateral walls of the furnace so that their outlet openings face each other, the burning dust jets will impinge against each other which will cause a large rising flame similar to that of ordinary grate firing. This flame will fill the entire furnace space and, in the case of locomotives, it will fill the entire fire box.

Inasmuch as the fire boxes of the various types of locomotives for instance are varied in design, in one instance being short and wide and in another instance long and narrow, the paths followed by the flames are likewise very different. In the short-and-wide design the above described way of introducing the fuel has given satisfaction because the individual dust particles have a sufficiently large path within which they may be consumed and because a sufficient time of combustion is attained thereby. The conditions are different, however, in the case of locomotives with narrow fire boxes, since here, with a vertical impinging of the coal dust jets, the time is not sufficient for complete ignition.

One object of my present invention is to provide an improved construction and arrangement whereby the path of the flames is lengthened and a better operation of the furnace is obtained. Another object of my invention is an improved arrangement of burners which permits a better operation of a furnace at low load.

For a consideration of what I believe to be novel and my invention, attention is directed to the following description and the claims appended thereto.

According to my invention, a multiplicity of nozzles is provided for ejecting the burn-

ing material at an angle such that the flames are directed towards the air of combustion which enters by way of the fire box wall. This arrangement insures the thorough mixing of the dust-air jets with the secondary air from the tube wall.

In the case of installations where the firing is continued for a considerable period at low load, it is not advisable to disperse the dust jets too much because, owing to the existing possibilities of heat radiation, too much heat may be withdrawn from the fire box, and this might cause extinction of the fire. Under these conditions, the arrangement may be such that all jets converge toward one point as much as possible. This is obtained, in accordance with one embodiment of the invention, by arranging the walls which define the outlet nozzles in a manner such that they may be turned or adjusted so as to direct together and in the desired directions the individual jets. This arrangement of nozzles can be applied to narrow as well as to wide fire boxes.

The direction which must be given to the fuel-air mixture upon leaving the slots of the burner tube can be obtained in different manners. For instance, the outlet slots may have such a shape that the fuel-air mixture is blown into the fire box in an inclined direction, or the guide vanes, which are provided in front of the outlet slots may be shaped in such a manner that they impart the desired direction to the dust-air mixture. Also, in special cases, the guide vanes may be made adjustable individually, in groups, or in their entirety, to regulate the trend of the path of the flames within the fire box so that the flames that come from different directions will meet in the center of the fire box.

In the drawings, wherein there is illustrated an embodiment of my invention, Fig. 1 is a vertical longitudinal sectional view through a locomotive fire box; Figs. 2 and 3 are sectional plan views taken on line 2-2, Fig. 1, showing different arrangements of the discharge nozzles of the burners, and Fig. 4 is a perspective view partly broken away of one of the discharge nozzles.

Referring to the drawings, 1 indicates the fire box, and 2 indicates the ash box. Direct-

ly above the ash box and in the lower portion of the fire box are two opposed burners 3 which are provided with walls forming discharge passages 4. Burners 3 extend along 5 the sides of the fire box and are preferably tapered in cross section from their admission ends to their discharge ends. The burners may be of any suitable construction. In 10 the present instance, referring particularly to Fig. 4, they are shown as each comprising a rectangular box 5, having a cover plate 6 in which are arranged spaced vertical discharge slots 7. Located between the discharge slots are walls or vanes 8 which define 15 discharge nozzles for the fuel and air issuing from the slots 7. Above and below the walls or vanes 8 are conduits 9 for the circulation of cooling water. The secondary air for combustion enters through a slot 10 formed in 20 the front wall 11 of the fire box just beneath the baffle plate 12. 13 indicates the tube sheet of the boiler and 14 indicates the boiler tubes.

According to my invention, I so construct and arrange the slots 7 and the walls or vanes 8 which define the discharge nozzles of the burner, that the fuel-air mixture issuing from them is discharged at an angle other than a right angle to the face of the burner and generally inclined toward the front wall 30 11 of the fire box. By this arrangement, the flame issuing from the nozzles is directed toward the front wall and flows against the air for combustion entering through the slot 10. In this manner, all coal-dust particles are 35 brought into contact with the air for combustion, and at the same time the path of combustion within the fire box is lengthened. Because of this lengthening, and particularly because of the intimate mixing of the 40 secondary air with the flame, all coal-dust particles will burn completely before they reach the tube sheet 13. It will be understood, in connection with a fire box of this type, that the flames which issue from the 45 opposite burners impinge against each other and rise gradually so that the entire fire box is filled with the flames.

The direction of the fuel-air mixture issuing from the burners may be defined by the 50 shape of the slots 7, or by the shape of the walls or vanes 8 which define the discharge nozzles, or by both means. If found desirable, the walls or vanes 8 which define the discharge nozzles may be made adjustable, 55 either individually or in groups. In the present instance, the walls or vanes 8 are shown as being suitably pivoted on the tubes 9, and as being connected together in groups by the rods 15, whereby they may be adjusted to 60 the desired positions. In Fig. 2 the burners are shown as being arranged to discharge the fuel-air mixture in a generally forward direction as indicated by the arrows. In Fig. 3 they are shown as being adjusted to 65 discharge partly in a forward direction and

partly in a rearward direction, as is indicated by the arrows, the jets being directed generally toward a common point.

In accordance with the provisions of the patent statutes, I have described the principle of operation of my invention, together with the apparatus which I now consider to represent the best embodiment thereof. It is to be understood, however, that the arrangement shown is only illustrative, and that the invention may be carried out by such other means as come within the scope of the appended claims.

What I claim as new and desire to secure by Letters Patent of the United States, is: 80

1. In combination, front, side and rear walls which define a fire box, said front wall having a passage for the admission of secondary air, a plurality of injection nozzles along the side walls of said fire box through which a fuel-air mixture is supplied, said nozzles being inclined to the direction of the axis of the fire box whereby they impart an inclined direction to the fuel-air mixture towards the direction of secondary air. 90

2. In combination, front, side and rear walls which define a fire box, said front wall having a passage for the admission of secondary air, channels along said side walls through which a fuel-air mixture is passed, a plurality of injection nozzles leading from said channels through which said fuel-air mixture is blown into the furnace, said nozzles comprising a plurality of guide vanes inclined towards the direction of the axis of said fire box for imparting to the fuel-air mixture an inclined direction towards the direction of said secondary air. 100

3. In combination, front, side and rear walls which define a fire box, said front wall being provided with a passage for the admission of secondary air, longitudinal channels provided at said side walls having a plurality of slots, and a plurality of adjustable guide vanes arranged between said slots. 110

4. In combination, front, side and rear walls which define a fire box, said front wall having a passage for the admission of secondary air, a plurality of injection nozzles along the side walls of said fire box comprising a plurality of guide vanes arranged in groups and directed towards the center of the fire box. 115

In witness whereof I have hereto set my hand this 5th day of October, 1929.

WALTER KLEINOW.
